(74) *Attorney, Agent, or Firm* — Robert C Montgomery; Montgomery Patent & Design

(57) **CLAIM**

The ornamental design for a lockable baton holster, as shown and described.

DESCRIPTION

FIG. 1 is a perspective front to back view of the lockable baton holster, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dashed lines are intended to show boundary areas and form no part of the design thereof.
